DESIGN FOR A WALL BRACKET FOR MEMORANDUM PAPER OR THE LIKE

Willis F. Sanford, Lakewood, Ohio

Application March 11, 1943, Serial No. 109,735

Term of patent 14 years

(Cl. D33—3)

To all whom it may concern:

Be it known that I, Willis F. Sanford, a citizen of the United States, residing in the city of Lakewood, county of Cuyahoga, and State of Ohio, have invented a new, original, and ornamental Design for a Wall Bracket for Memorandum Paper or the like, of which the following is a specification, reference being had to the accompanying drawing, forming a part thereof.

bracket for memorandum paper or the like, showing my new design;

Figure 2 is a front elevational view; and

I claim:

The ornamental design for a wall bracket for memorandum paper or the like, substantially as shown.

WILLIS F. SANFORD.
